UNITED STATES PATENT OFFICE.

LOU OBSTFIELD, OF BROOKLYN, NEW YORK, ASSIGNOR TO MARKWELL MANUFACTURING CO. INC., OF NEW YORK, N. Y., A CORPORATION OF NEW YORK.

DESIGN FOR AN ADVERTISING CARD OR THE LIKE.

Application filed October 19, 1927. Serial No. 23,809. Term of patent 7 years.

To all whom it may concern:

Be it known that I, Lou OBSTFIELD, a citizen of the United States of America, and a resident of the borough of Brooklyn, Kings county, city and State of New York, have invented a new, original, and ornamental Design for an Advertising Card or the like, of which the following is a specification, reference being had to the accompanying drawing, forming part thereof.

The figure is a plan view of an advertising card showing my new design, the same being of no appreciable thickness.

I claim:

The ornamental design for an advertising card or the like, substantially as shown and described.

LOU OBSTFIELD.
